UNITED STATES PATENT OFFICE.

GEORGE S. NORRIS, OF BALTIMORE, MARYLAND.

BOTTLE-STOPPING DEVICE.

SPECIFICATION forming part of Letters Patent No. 257,746, dated May 9, 1882.

Application filed February 16, 1882. (No model.)

To all whom it may concern:

Be it known that I, GEORGE S. NORRIS, a citizen of the United States, residing at Baltimore, in the county of Baltimore and State of Maryland, have invented certain new and useful Improvements in Bottle-Stopping Devices, of which the following is a specification.

This invention relates to bottle-stopping devices in which a rubber plug is compressed over and within the mouth of a bottle by means of a combined stopper cap and bail adapted to be connected at one end by means of a link and a hinged lever to a band secured to the neck of said bottle, and at the other end by means of a branch or extension projecting upward from said band; and the objects of my improvements are, first, to provide a rubber plug with a collar in the middle of its length, and capable of being reversed and either end inserted in the mouth of a bottle; second, to combine with said plug a cap provided with a shank passing therethrough, and also with ears on two sides thereof, a link permanently secured to one of the ears, and a wire lever adapted to enter said link and transfix it into engagement with the under side of the neck-band.

Heretofore rubber plugs have been made with a collar to rest upon the edge of a bottle-mouth, while its lower portion enters within. They have also been made with a central collar and projection above and below of uneven size, and thus not reversible. Neck-bands have also been made of twisted wire having a horizontal loop on one side to receive a lever pivoted thereto, and said lever has been made to remain in engagement with a link pendent from the stopper-cap while the bottle is closed; but these parts differ from mine in many particulars.

The invention will first be described in connection with the drawings, and then pointed out in the claims.

In the drawings, Figure 1 represents a perspective view of the bottle-stopping device secured over a bottle-mouth. Fig. 2 represents a vertical section of the same. Figs. 3 and 4 represent, respectively in perspective and vertical section, the stopper-plug detached from its fastenings. Fig. 5 represents in perspective the wire lever detached from the neck-band.

In said drawings, A represents the neck of a bottle, B the rubber plug, and C the metal cap placed upon the plug B, and connected therewith by the shank c thereof passing 55 through its axis.

The plug B is of peculiar construction. It is provided with a collar, b, surrounding it in the middle of its length, a head, b', upon which the metal cap can rest, and a neck, b², adapted 60 to enter the mouth of a bottle.

The head b' and the neck b² are of identical form and size when first molded, as shown in Figs. 3 and 4, so that either one can take the place of the other when the plug is secured to 65 its cap. The plug is thus reversible, and the form given thereto contributes materially in improving the results obtained from a rubber stopper.

Although rubber is a very elastic substance 70 it is well known that when retained compressed for some time its form will become more or less set and lose the form first given thereto when molded. By making the rubber plug reversible end for end this defect is remedied, 75 the change being made once or twice a year, or when the rubber has lost so much of its original form as to be partly ineffective as a stopper.

It is clearly shown in Fig. 2 that under 80 pressure the lower end of the plug inserted in the bottle is reduced in diameter, while the upper end or head partly bulges out, and thus acquires strength against circular compression, to which it will be subjected if the plug is afterward turned end for end and its head is made to enter the neck of the bottle.

This stopper-plug is preferably conically recessed at each end at b³ to facilitate the insertion thereof in the neck of the bottle, and also 90 to permit said plug to retain its effectiveness more readily by providing room for the arrangement of its central molecules, as the plug cannot expand laterally in the neck of the bottle.

The plug is also provided with an axial opening, b⁴, for the passage of the metal cap-shank c, the latter being formed with an enlarged end or button, c', capable of passing under pressure through the opening b⁴, but of such size as to retain the plug securely connected 100 to its cap. This cap C is in the form of a disk provided with two perforated ears, c², to re-

ceive one end of the link and one end of the neck-band, branch, or extension that unites it to the band E, encircling the neck of the bottle. This band is shown as made of a piece of wire so bent as to form a nearly rectangular but substantially horizontal loop, e, on one side of the bottle-neck, while upon the other side said wire is twisted to form a branch or cable, e', extending up nearly even with the mouth of the bottle. This branch e' has its upper end looped, and engages with one of the ears e² of the stopper-cap, while to the opposite ear the link f is permanently secured. The lower loop of this link f is made of such width as to readily pass over and clasp the rectangular loop e of the neck-band.

The operating-lever G of the device is formed of suitable-size wire bent upon itself in the middle of its length, and coiled adjoining to the ends thereof to form a cylindrical bearing, g, adapted to receive the wire of the neck-band, and is placed upon said neck-band between the side branches of its rectangular loop e.

25 The ends g' of the wire forming the operating-lever G project inwardly toward the neck of the bottle a sufficient distance to engage with the lower loop of the link f and force it from its seat under the neck-band when the bottle is to be opened.

30 The lever G is curved in such manner that its concave surface engages with the link f in closing the bottle, and facilitates its transfer under the loop of the neck-band, and as it remains secured against the side of the bottle by its ends g' its outer surface is convex and smooth, and has no projection to cause it to be accidentally turned outward.

35 In closing the bottle the stopper-plug is placed over the bottle-mouth, the free end of the lever G is passed through the lower loop of the link f, and said lever is pressed downward, the link sliding upon the concave side of the lever until it rests upon the convex cylindrical portion of the bearing g thereof, and in bringing the lower end of the lever against the side of the bottle the link slides off the cylindrical portion g to the under side of the bottle-collar, against which it rests, and thereby 40 by or thus relieves the lever and its bearing of all strain, although the link f is thereby doubly locked.

45 The bottle is opened by simply pulling the lever G outwardly, its ends g' removing the link from its seat. The resilience of the stopper causes it to leave its seat and to swing out of the way with its cap around its hinged ear.

Having now fully described my invention, I claim—

1. A bottle-stopping device composed of an elastic plug having in the middle of its length a collar adapted to rest upon the edge of a bottle-mouth, a head above said collar, and a neck thereunder, said head and neck being formed with the same periphery and provided with a conical recess, b², being adapted for use alternately, substantially as and for the purposes described.

2. In a bottle-stopping device, the combination of an elastic plug perforated through the center thereof, and having a collar adapted to rest upon the edge of a bottle-mouth, a head projecting above said collar, and under said collar a neck provided with a central conical recess, with a metal cap adapted to cover the head of the stopper, and provided with a shank passing through the stopper.

3. In a bottle-stopping device, the combination of an elastic plug perforated through the center thereof, and having a central collar adapted to rest upon the edge of a bottle-mouth, and two ends adapted to be used and each one inserted alternately within said bottle, with a metal cap adapted to cover either end of the plug, and the shank of said cap passing through the stopper, substantially as and for the purpose described.

4. The combination of a bottle neck-band consisting of a wire bent and twisted to form a vertical looped branch upon one side and a loop, e, upon the other, with a stopper-cap provided with ears e², a link, f, permanently secured to one of the ears and adapted to engage with the under side of the loop e of the neck-band, and a lever, G, pivoted upon the neck-band and consisting of wire bent and coiled to form a bearing adapted to engage with the loop e, and present a convex surface for the link f to slide over, substantially as and for the purpose described.

5. The combination of a bottle neck-band having a looped branch upon one side and a loop, e, upon the other, with a stopper-cap provided with ears, a link, f, permanently secured to one of the ears and adapted to engage under the loop e, and a lever, G, constructed to form a bearing adapted to engage with the loop e and present a convex surface for the link f to slide over, with projection g', substantially as and for the purpose described.
